AUTOMATIC FILLING GUIDE FOR TEXTILE LOOMS

Chester N. Perry, North Vassalboro, Maine

Application February 7, 1949, Serial No. 74,908

13 Claims. (Cl. 139—116)

1

The present invention relates to new and useful improvements in attachments for textile looms and more particularly to means for subjecting the filling to a constant drag as it comes off the shuttle to prevent backlash which causes imperfect weaving commonly known as "side lines."

An important object of the invention is to provide a guide attached to a part of the loom adjacent the filling and a brush, or pad, of suitable material for holding the filling against the guide to maintain the filling in a taut condition.

A further object of the invention is to provide means for automatically raising and lowering the brush or pad in accordance with the movement of the shuttle box and to further construct the brush or pad for the engagement of the filling in the brush to raise and lower the filling above or below the line of filling from a previous shuttle.

Another object of the invention is to provide a filling guide which will not interfere with the action of the weaver when driving his shuttle into the shuttle box, or when throwing his shuttle through the shed of the warp.

A still further object is to provide an attachment of this character of simple and practical construction, which may be easily mounted in position on a loom without necessitating any changes or alterations in the construction thereof and which, at the same time, is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a front elevational view;

Figure 2 is a top plan view with parts broken away and shown in section;

Figures 3 and 4 are enlarged transverse sectional view taken respectively on the lines 3—3 and 4—4 of Figure 1;

Figure 5 is a group perspective view of the several parts of the upper and lower brush holder; and

Figure 6 is a perspective view of a fur pad for use with the guide in place of a brush.

Referring now to the drawings in detail wherein, for the purpose of illustration, I have disclosed a preferred embodiment of the invention, the numeral 5 designates the usual casting of a loom on which a reed cap 6 and race plate are supported. Shuttle boxes 8 and 9 are shown posi-

2

tioned at each end of the race plate and which carry the shuttles 10 positioned one above the other in the shuttle box for aligning with the race plate 7.

5 A shuttle guard 11 is secured at each end of reed cap 6 and is formed at its lower portion with an arcuate shoe 12 positioned immediately above the race plate 7.

A resilient filling guide 13 comprising a strap metal plate is provided adjacent one end with a longitudinal slot 14 for securing in a vertically adjusted position behind the reed cap 6 by a bolt and wing nut 15, the metal strap extending upwardly and over the top of the reed cap and

15 downwardly in front thereof and with its lower end indicated at 16 bent inwardly and frictionally held in the arcuate shoe 12 of the shuttle guard. The front surface 17 of the filling guide 13 is positioned above the race plate 7 to form a guide

20 for the weft thread or filling 4 of the shuttle during its movement, and the filling is held in engagement with the vertical surface 17 of the filling guide 13 by an upper brush or bristle-like member 18 and lower brush or bristle-like member 19.

25 The upper brush 18 is provided with a twisted wire core 20 which usually provides a handle for the brush and which, in the present instance, provides a twisted wire supporting arm which is bent angularly for the insertion of its end in an opening 21 of a brush holding block 22. The arm 20 of the brush is held in the opening 21 by a set screw 23 to support the brush 18 in a vertical position in front of filling guide 13.

The lower brush 19 includes a lower horizontal portion 24 and an upper vertical portion 25 which is held against one side of the upper brush 18 in an overlapping relation with respect thereto by means of a twisted wire core 26 inserted upwardly in the bottom of the brush holding block 22 and secured therein by a set screw 28.

30 The block 22 is formed with a horizontal slot 29 for slidably and pivotally mounting the block on a smooth portion 30 of a screw 31 threaded in an opening 32a adjacent one end of a substantially triangular shaped arm 32 to hold the block 22 against the outer surface of the arm. A stem 33 projects from the inner surface of arm 32 adjacent its end opposite from screw 31, the stem 33 being received in a bearing 34 of a bracket 35 secured to reed cap 6 for rockably supporting the arm thereon. The bracket 35 is secured to the reed cap by means of a bolt 36 positioned in a boss 37 on the bracket and projecting outwardly therefrom.

35 A plate 38 is secured at one end to the outer

end of boss 37 by screws or the like 39 passing through openings 38a in plate 38 and threaded into openings 37a in boss 37, and the other end of the plate is formed with upper and lower stops 40 and 41 positioned respectively above and below block 22. The block 22 is held against the end of plate 38 between stops 40 and 41 by means of a coil spring 42 connected at one end to a pin 43 carried by plate 38 and connected at its other end to a pin 44 carried by block 22.

A screw 45 is also carried by plate 38 with its inner end abutting arm 32 to prevent end play of stem 33 in bushing 34, the screw 45 being adjusted relative to arm 32 by means of a nut 46.

A wire arm 47 has one end secured in an opening 48 at the free end of arm 32 by means of a set screw 49, the wire arm 47 having its other end extended downwardly and formed with a foot 50 loosely resting on the top of shuttle box 8.

One of the filling guide attachments is placed at each end of the reed cap 6 for use with each shuttle box 8 and 9, the attachments being suitably constructed to form a "right" and a "left" for positioning respectively at the right and left of the loom, each attachment functioning in a similar manner.

The brushes 18 and 19 are free at their lower ends whereby the weft thread or filling 4 may be easily placed upwardly in position behind the brushes or removed therefrom, and as the shuttles are moved along race plate 7, the weft or filling passes between the guide 13 and brushes 18 and 19, the brushes holding the filling taut to prevent slack therein and thus avoid "side lines" or similar defects in the weave.

As the shuttle box 8 or 9 is raised or lowered, the arm 47 is likewise raised or lowered and transmits this motion to the pivoted arm 32 and block 22 which carries brushes 18 and 19, the filling being engaged in the bristles of the brush whereby one line of filling is kept out of the course of the next line from a succeeding shuttle.

The upper and lower stops 40 and 41 limit the movement of block 22 and the block slides on pin 38 carried by pivoted arm 32 and is held perpendicularly against the end of plate 38 by spring 42 to maintain the brushes in a perpendicular position against guide 13 during raising and lowering movement to avoid twisting of the filling engaged by the brushes.

If desired, a fur or other suitable pad or tufted member 50 having a filling engaging nap or tufted surface 51 and held taut in a wire frame 52 may be interchangeably attached to block 22 in place of the brushes.

The upper brush 18 is needed at all times and lower brush 19 is necessary when more than two shuttles are in use. Both brushes are held in a perpendicular position by spring 42 holding the block 22 against the end of plate 38, except as affected by the movement of the weft (filling) which, in the event of a backlash might cause a rotation of block 22 swinging the lower horizontal end 24 of lower brush 19 upwardly into a perpendicular position to at all times provide a perpendicular brush for the weft. The use of both brushes eliminates the usual delay in changing the loom over from two to four shuttles and enables continuous and uninterrupted operation with two or more shuttles.

The brushes may be adjusted relative to guide plate 13 as required with respect to fine or coarse filling being used to the point necessary to engage the filling and apply the necessary drag.

Having described the invention, what is claimed as new is:

1. In a loom, the combination of a vertically movable shuttle box and a race plate for receiving shuttles from the box, and a filling guide for the filling of the shuttles and comprising a stationary vertical guide plate supported by the loom adjacent the entrance to the race plate, means adjacent the guide plate holding the filling taut, and means actuated by the vertical movement of the shuttle box for similarly moving the first-named means and the filling held thereby.

2. In a loom, the combination of a vertically movable shuttle box and a race plate for receiving shuttles from the box, and a filling guide for the filling of the shuttles and comprising a stationary vertical guide plate supported by the loom adjacent the entrance to the race plate, a tufted member supported by the loom in a position opposed to the guide plate and between which the filling passes in contact with the member for holding the filling taut, and means actuated by the vertical movement of the shuttle box for similarly moving the tufted member and the filling held thereby.

3. In a loom, the combination of a vertically movable shuttle box and a race plate for receiving shuttles from the box, and a filling guide for the filling of the shuttles and comprising a stationary vertical guide plate supported by the loom adjacent the entrance to the race plate, a brush supported by the loom in a position opposed to the guide plate and between which the filling passes in contact with the brush for holding the filling taut, and means actuated by the vertical movement of the shuttle box for similarly moving the brush and the filling held thereby.

4. In a loom, the combination of a vertically movable shuttle box and a race plate for receiving shuttles from the box, and a filling guide for the filling of the shuttles and comprising a stationary vertical guide plate supported by the loom adjacent the entrance to the race plate, a tufted pad supported by the loom in a position opposed to the guide plate and between which the filling passes in contact with the pad for holding the filling taut, and means actuated by the vertical movement of the shuttle box for similarly moving the pad and the filling held thereby.

5. In a loom, the combination of a vertically movable shuttle box and a race plate for receiving shuttles from the box, and a filling guide for the filling of the shuttles and comprising a stationary vertical guide plate supported by the loom adjacent the entrance to the race plate, a bristle-like member supported by the loom in a position opposed to the guide plate and between which the filling passes in contact with said member to hold the filling taut, and means actuated by the vertical movement of the shuttle box for similarly moving said member and the filling held thereby.

6. In a loom, the combination of a vertically movable shuttle box and a race plate for receiving shuttles from the box, and a filling guide for the filling of the shuttles and comprising a stationary vertical guide plate supported by the loom adjacent the entrance to the race plate, an arm pivoted on the loom for vertical swinging movement, means carried by the arm and engaging the shuttle box for actuation thereby, and a bristle-like member connected to the arm and engaging the filling to hold the same taut.

7. In a loom, the combination of a vertically

movable shuttle box and a race plate for receiving shuttles from the box, and a filling guide for the filling of the shuttles and comprising a stationary vertical guide plate supported by the loom adjacent the entrance to the race plate, an arm pivoted on the loom for vertical swinging movement, means carried by the arm and engaging the shuttle box for actuation thereby, a bristle-like member attached to the loom in a position for contact with the filling to hold the filling taut, and means rockably supporting the bristle-carrying member on the arm and holding said member moving in a perpendicular position with respect to the guide plate during vertical movement of the arm.

8. In a loom, the combination of a vertically movable shuttle box and a race plate for receiving shuttles from the box, and a filling guide for the filling of the shuttles and comprising a stationary vertical guide plate supported by the loom adjacent the entrance to the race plate, an arm pivoted on the loom for vertical swinging movement, means carried by the arm and engaging the shuttle box for actuation thereby, a block rockably supported on the arm, a bristle-like member connected to the block in a position for contact by the filling to hold the filling taut, and fixed guide means for the block holding said member moving in a perpendicular position relative to the guide plate.

9. In a loom, the combination of a vertically movable shuttle box and a race plate for receiving shuttles from the box and a filling guide for the filling of the shuttles and comprising a stationary vertical guide plate supported by the loom adjacent the entrance to the race plate, a plurality of vertically overlapping tufted members supported by the loom in a position opposed to the guide plate and between which the filling passes in contact with said members for holding the filling taut, and means actuated by the vertical movement of the shuttle box for similarly moving the tufted members and the filling held thereby.

10. In a loom, the combination of a vertically movable shuttle box and a race plate for receiving shuttles from the box and a filling guide for the filling of the shuttles and comprising a stationary vertical guide plate supported by the loom adjacent the entrance to the race plate, a filling supporting member mounted on the loom at one side of the guide plate and composed of loosely

united fibers engaging the filling passed by the respective shuttles and holding the filling taut and separated from adjacent fillings, and means actuated by the vertical movement of the shuttle box for similarly moving the filling supporting member and the filling held thereby.

11. In a loom, the combination of a vertically movable shuttle box and a race plate for receiving shuttles from the box, and a filling guide for the filling of the shuttles and comprising a stationary guide plate attached to a part of the loom adjacent the entrance to the race, and a flexible guide member opposed to the guide plate and between which the filling passes.

12. In a loom, the combination of a vertically movable shuttle box and a race plate for receiving shuttles from the box, and a filling guide for the filling of the shuttles and comprising a stationary guide plate attached to a part of the loom adjacent the entrance to the race, and a flexible guide member opposed to the guide plate and between which the filling passes, said flexible guide member being composed of loosely united fibers with which the filling is frictionally engaged.

13. In a loom, the combination of a vertically movable shuttle box and a race plate for receiving shuttles from the box, and a filling guide for the filling of the shuttles and comprising a stationary guide plate attached to a part of the loom adjacent the entrance to the race, and a flexible guide member opposed to the guide plate and between which the filling passes, said flexible member being composed of loosely united fibers with which the filling has wiping contact.
